UNITED STATES PATENT OFFICE.

CHARLES J. REED, OF ORANGE, NEW JERSEY, ASSIGNOR OF ONE-THIRD TO
GUSTAV STAHL, OF PHILADELPHIA, PENNSYLVANIA.

ELECTRIC-RAILWAY SYSTEM.

SPECIFICATION forming part of Letters Patent No. 500,104, dated June 20, 1893.

Application filed June 27, 1892. Serial No. 438,115. (No model.)

To all whom it may concern:

Be it known that I, CHARLES J. REED, a citizen of the United States of America, residing at Orange, in the county of Essex and State 5 of New Jersey, have invented certain new and useful Improvements in the Art of Electric Propulsion, of which the following is a specification.

My invention is directed to novel methods 10 of and apparatus for propelling moving vehicles through the agency of electricity as a motive power, and particularly to that type of electric railways in which the conductors that supply the current are located beneath 15 the surface of the earth, and known in the art as "conduit systems."

Its objects are, first, to provide a conduit system which may be cheaply constructed and will be located near the surface of the 20 earth; second, to combine with such a conduit system a source of electrical storage supply on each vehicle which shall receive a sufficient supply in each instance to propel the vehicle over a definite space in the event of 25 any mishap to the conduit system at any point throughout its entire circuit; third, to construct a conduit or subway system of contact or trolley conductors and circuit connections in such manner as to afford a minimum 30 amount of current leakage and hence a maximum efficiency; fourth, to provide means whereby any vehicle may be caused to pass over any section of the road-way which is submerged with water and to enable the propelling motor of the vehicle to be again connected with the circuit after such point has 35 been safely passed; fifth, to accomplish any and all results naturally attributable to the operation of the system in its entirety as hereinafter described, the especial novel features 40 whereof both as to the details of construction and mode of operation being particularly pointed out in the claims at the end of this specification.

In order that my invention may be fully understood reference is had to the accompanying drawings and to the following specification which is a full, clear, and exact description thereof.

Figure 1 of the drawings is a longitudinal sectional view of a portion of my improved

subway trolley system illustrating a single tram car in position, with a propelling electric motor carried thereby and operatively connected through the circuit connections in 55 the conduit. Fig. 2 is a transverse section of a tram car road-bed embodying also my improved conduit located in the center thereof between the rails. Fig. 3 is a diagrammatic view illustrating my improved system 60 in combination with means for ventilating and drying the tubes or pipes which inclose the mains or conductors. Fig. 4 is a diagrammatic view of my improved storage system applicable to each car or vehicle and illustrating also the circuit connections with the 65 conduit mains, the trolley brushes and the motor on board of the vehicle. Fig. 5 is a vertical sectional view taken through the body of the conduit in such manner as to 70 illustrate in vertical elevation the circuit closing devices which complete the circuit from the buried conductors to the motors on board of the cars, there being a definite number of such circuit closing devices located at 75 stated intervals of from twenty to thirty feet. Fig. 6 is a similar vertical sectional view illustrating a modified form of mechanically controlled circuit closing devices, that shown in Fig. 5 being of electro-magnetic construction. Fig. 7 is a horizontal sectional view taken through Fig. 5 on the line $x-x$ and as 80 seen looking in the direction of the arrows from the top toward the bottom of the drawings. Fig. 8 is a similar horizontal sectional view taken through Fig. 5 on the line $y-y$ and illustrating the circuit closing connections with the inclosed conducting mains located on either side of the slotted conduit. Fig. 9 is a horizontal sectional view of a portion 85 of Fig. 5 on line $z-z$ and as seen looking from the top toward the bottom of the drawings. Fig. 10 is a detail sectional view illustrating the circuit shifting apparatus utilized in connection with the sections of 90 storage battery shown also in diagrammatic and plan view in Fig. 4.

Prior to my invention it was old in the art to bury one or more mains or leads beneath the surface of the road-bed and to provide 100 sectional circuit closing devices located at fixed distances apart and manipulated by the

car as it advanced in such manner as to close the circuit through a propelling motor on board of the car and again rupture the circuit the instant after the circuit was closed 5 through the next succeeding circuit closing device in advance thus leaving all of the sectional circuit closers normally out of connection with the mains or leads except such as were within the immediate control of the passing car. It was also old in the art to force currents of air through pipes or tubes which inclose the mains or leads of an electric railway provided with sectional circuit closing devices of the general nature just referred to. Storage batteries have also been used in connection with subway trolley systems but in all instances, so far as I am aware, where it has heretofore been proposed to so use such a supplemental supply of electrical energy, it 10 was proposed that the storage capacity of the battery should be such as to entirely supplant or take the place of the contact or trolley system with which they were to be used. My invention in so far as this feature of it is concerned differs from all that have heretofore been suggested, in that I utilize a minimum amount of storage capacity only just sufficient to meet the most extensive demand that may be made upon it at any part of the roadway and not of sufficient capacity to carry the car over a distance greater than say half of the route.

To illustrate my meaning upon all those portions of the road-way where there are appreciable grades or where the road-bed is of such a nature that it may be readily and quickly drained, I propose to propel the vehicles upon the contact or trolley principle and to at the same time charge a storage battery 35 carried by the car which storage battery shall have only sufficient ampère hour capacity to run the car for a short space of time, say two, five or ten minutes and utilize this battery of small capacity on those portions of the road which are liable to be submerged during a severe rain storm or at street crossings or curves, the arrangement being such 40 that the contacting shoe or trolley bar shall be lifted out of the conduit slit at all such points, said slit being for all practical purposes discontinued at all crossings, curves, and other places where there is any liability 45 of disturbances or troubles at any time due to its presence. The current mains connected directly to the dynamo located at the power house are insulated throughout their entire length and are provided with switch boxes at stated intervals having normally open circuit making and breaking devices adapted to 50 connect them to short sectional branch conductors with the trolley or shoe carried by a car or vehicle as it passes over the route, the arrangement being such that the trolley sections or short normally open branch conductors are operatively connected with the propelling motor and the storage battery simultaneously. By utilizing a storage battery of

small ampère hour capacity I am enabled to propel a vehicle for a brief space of time with a minimum weight of propelling battery and 70 by so arranging the circuit connections that at each time that the contact shoe or trolley is lifted from the slotted conduit I am enabled to shift the circuit connections from one section of battery already charged to an additional section of battery not so fully charged as that which has just been cut out of the charging circuit thereby bringing into the working circuit each time that the trolley shoe is lifted a charged section of battery 75 and cutting out a similar section of battery the next time the trolley shoe is lifted, thus maintaining the batteries which are in the charging circuit with a minimum counter electro-motive force and allowing them to exert a maximum electro-motive force when furnishing current to the motor alone.

Referring now to the drawings in detail: C' represents a slotted conduit made preferably of cast iron and of two pieces bolted securely 90 to the cross ties T of a railway beneath the road-bed and provided at its bottom with drainage openings d d which are connected to a drain pipe D'. At intervals of from twenty to thirty feet are located switch boxes 95 B' made in detachable sections and secured to the lower or web portions of the slotted conduit by bolts b³ b³ (see Figs. 5, 6, 7 and 8.)

D² D² are metallic pipes or tubes secured to the opposite sides of the slotted conduit C' through the agency of the switch boxes B' into and through which they extend being provided on the interior of said boxes with screw threaded sleeves f. These pipes or tubes are water tight and inclose respectively, 100 the advance and return mains w w' connected directly to the poles of a generator or dynamo electric machine D located at the power house. These metallic pipes or tubes are also connected directly to a heater H and a desiccator or drier D³ and air pump or blower P³ also located at the power house, the arrangement being such that the pump or blower P³ will force air continuously through the heater H to the pipes D² and drier D³ keeping up a continuous circulation of the air in the pipes about the feeders or mains w w' and subjecting them to the drying influence of any well known desiccating or drying substance placed in the desiccating device D³.

C (Fig. 1) represents a tram car standing upon the rails R R carried by sleepers O O (see also Fig. 2).

S is a trolley shoe or bar provided with conducting plates m² m² upon its lateral faces insulated from each other and adapted to pass between the contacting brushes b b' carried by angular arms a a pivotally secured in long pivot bearings in insulating standards m and detachable from upwardly extending necks 120 in the screw threaded sleeves f f and carrying at their upper ends inverted cups or bells c' c'.

I will first describe the form of circuit clos-

ing device shown in Figs. 5 and 7 which is of an electro-magnetic nature and in which the trolley shoe or bar at its lower edge is of iron or other magnetic material and adapted to become magnetic throughout its length by an insulated conducting coil m' which is connected electrically with the circuit by conductors running to the side contacting plates m^2 m^3 and to the trolley brushes as will be described in connection with the description of the mode of operation.

d d are rollers made of magnetic material and secured by bolts and insulating brackets to the under side of the angular arms a a at points intermediate the pivot rods t t and the conducting trolley brushes b b' , their function being when magnetized through the agency of the magnetic trolley shoe to withdraw the contacting brushes b b' from their inner or concealed position shown in dotted lines in Fig. 7 to the outer or contacting position shown in full lines in plan view in the same figure, and in elevation in Fig. 5.

s s are spiral springs each secured at its lower end to one of the long insulating journal bearings m and at its upper end to the pivoted end of one of the angular arms a , the arrangement being such that under normal conditions the spiral springs will tilt or turn the angular arms a together with the rollers D and contacting brushes b b' into their inner or concealed positions in the switch boxes B' as shown in dotted lines in Fig. 7, it being understood that at those points of the slotted conduit surrounded by the switch boxes B' there are lateral openings for permitting such movement.

The switch boxes B' are provided with removable covers C C and the bells or cups c c' which cover the upper ends of the conducting angular arms a and a portion of the upper ends of the long insulating journal bearings m may be removed, the spiral springs s s detached and the journal bearings t t lifted out of their sockets v and disconnected from the lower pivotal portions which carry brushes b^2 b^2 adapted to contact directly with the mains or leads w w' proper sustaining devices being secured to the mains within the sleeves f for the purpose of preventing the mains from being disturbed mechanically, such sustaining devices of course being properly insulated and so arranged as not to seriously impede the inflow and outflow of air from the blower and heater at the power house. The function of the bells or cups c c' is to prevent any possibility of serious effects from flooding the conduit, it being apparent that water cannot rise in said bells if they are properly constructed and secured to the insulated standards m .

In the form shown in Fig. 6 the magnetic portion of the trolley shoe or bar is done away with and the operation of the pivotal circuit closers is effected through the agency of a V shaped extension K of the trolley shoe or bar S which bears upon grooved rollers r r pivot-

ally secured to the bottom or T portion of the slotted conduit through the agency of bell crank levers l l the upper or free ends of which are adapted to bear against lugs or projections g g located near the middle and on the under side of the angular conducting arms a a , the pivotal supports and attachments of which are identically the same as those of the like parts shown in Fig. 5.

Referring now to Figs. 1 and 4, but more particularly to the latter, I will describe my novel arrangement for utilizing stored up electrical energy in connection with electric propulsion. D represents the dynamo connected directly to the current mains w w' , the arrangement being the same as disclosed in connection with Fig. 3 and S the trolley shoe or bar similar to that shown in Figs. 1 and 5 85 or 6, w^3 , w^6 , and w^8 being the conductors running from the trolley shoe to bus wires w^4 w^5 and switches S^w S^w and rheostats R^h R^h all carried by the car. B is the storage battery made up of any desired number of sectional parts 1, 2, 3, 4, 5, &c. M is the motor carried by the car and geared thereto in the usual manner. R is a rack (see Fig. 1) extending from one end of the car to the other provided with rack teeth adapted to mesh with pinions P P carried by operating levers L L' . P' P' are additional pinions meshing with teeth upon the same rack and operatively connected through downwardly extending arms E E with the trolley shoe or bar S , it being pivoted thereto at the points h h . P^2 is a similar pinion the teeth of which mesh with an additional set of rack teeth on the upper face of the rack R , and F is a shaft which is connected to the aforesaid pinion by ratchet and pawl mechanism, the arrangement being such that each time that the trolley shoe is lifted out of the slit by rotating the operating lever L in a given direction the pinion P^2 will make a fifth portion of a complete revolution and bring the lugs A , A' , A^2 , A^3 and A^4 successively into frictional relation with the pivoted switch levers L , L' , L^2 , L^3 and L^4 thereby successively disconnecting one section of the battery from the charging circuit and simultaneously connecting thereto an additional section, the arrangement being such that the sections of battery 1, 2, 3, 4, &c., will be cut out of the charging circuit in succession as the trolley shoe is lifted out of the slotted conduit and cut in again in the same order after four complete manipulations. In other words each section of battery will be disconnected from both the charging and discharging circuit in turn until the shaft F has made a complete revolution in a forward direction, it being understood that it remains stationary during the time that the trolley shoe or bar is being returned to the conduit and until said shoe is again lifted.

Fig. 10 illustrates in detail the operation of the circuit closing levers L L' , &c., it being understood that when the short arms of the levers are free from the lugs or spurs a , a' ,

a^2, a^3 or a^4 the long ends which are provided with contact plates insulated from each other are inserted between the yielding contact springs s^1, s^2, s^3, s^4 . As shown in the drawings 5 the spur or lug a is resting under the short arm of the lever L and its free end is therefore held in an upright position so that the contact springs s (see Fig. 4) rest against each other but out of contact with the plates 10 joined to the terminals of that section of battery. The remaining sections 2, 3, 4, 5, &c., are therefore being charged in series and are in multiple arc relation with the motor M which is propelling the car.

15 I will now describe the mode of operation. The trolley shoe or bar S being in the position shown in Figs. 1 and 5 the switch S^w is turned into position shown in Fig. 4 and the current passes from the storage battery commencing at section 5 thereof by way of the right hand contact spring s^4 in the direction of the arrows through conductors w^7, w^8 , side trolley contact plate m^2 , the coils of the electro-magnet m' in the base of the trolley shoe, 20 the other side contact plate m^2 , conductor w^8 , through the left hand switch S^w , rheostat R^h , bus conductor w^5 , conductors w^6, w^7 , contact springs s the first section of storage battery No 1 being out of circuit, thence through 25 sections Nos. 2, 3 and 4 of the storage battery and the contact springs s, s', s^2, s^3 back to the starting point. This energizes the trolley shoe magnet and causes the magnetic rollers d of that pair of the circuit closing devices 30 between which the trolley shoe happens at that instant to rest to be drawn into their outward or contacting position as shown in Figs. 5 and 7 in full lines. Immediately therefore the trolley brushes b, b' are drawn into 35 contact with the side plates m^2, m^2 and current is taken directly from the dynamo D and mains w, w' as is indicated by the arrows in Fig. 4 of the drawings, the electric motor M being in multiple arc relation with the 40 storage battery. As the car advances therefore the trolley shoe or bar S passes between the next pair of pivoted contacting brushes in advance before it leaves the pair of brushes just described and they are in line when drawn 45 into their outer position into contact with the conducting side plates m^2, m^2 and so in succession these pairs of brushes are brought into operative relation, the car caused to advance and the storage battery simultaneously 50 charged. When the car reaches a street crossing or curve in the track where the continuity of the slotted conduit is broken as shown in Fig. 1, the attendant through the agency of the operating lever L imparts to the rack 55 and R a motion in the proper direction to rotate the pinions P, P' thereby lifting the shoe or bar S out of the slit, thus rupturing the circuit between the shoe and such of the circuit closing devices as may be in contact with it 60 at that time. At the same time rotary motion is imparted to the pinion P^2 and the shaft F , thereby releasing the lever L from the influ-

ence of the lug or projection a and allowing the spiral spring connected to said lever to draw it into its reverse position so as to force 70 the conducting plates on its free end between the contact springs s thus throwing section No. 1 of the battery into circuit. The same forward rotation however of the shaft F was sufficient to cause the second lug or projection 15 a' to leave the lever L and disconnect section No. 2 of the battery from the circuit. The car will however continue in motion now by virtue of the storage battery only, the main circuit being ruptured and the storage battery 80 being closed through the motor as follows: from section No. 5 by contact spring s^4 , wire w^7 , switch S^2, w , wire w^6 , motor M , conductor w^7 , section No. 1 of the battery contact springs s^1 , section No. 2 being now out of circuit, contact springs s^2 , section No. 3, contact springs s^3 , section No. 4, back through section 85 No. 5 to the starting point. After the car has passed that portion of the roadway included between two successive sections of slotted conduit, the attendant lowers the trolley shoe or bar S into the slit and current is again taken from the current mains as before. At each curve therefore of the roadway or at any submerged portion of the conduit the attendant 90 may lift the trolley shoe or bar and allow the motor to be operated wholly by the storage battery or in the event of severe rain storms cars may be run wholly by the storage battery 95 by stopping at elevated points of the road-way and storing current to be used on the depressed 100 or submerged portions of the track.

The operation of the modified form of circuit closing devices illustrated in Fig. 6 will be apparent in view of the description of the 105 operation with relation to Fig. 5, it being understood that as the trolley shoe advances the pivoted levers l are operated mechanically by the action of the extension K upon the grooved rollers r , the upper ends of the levers 110 l being forced into mechanical contact with the insulated lugs g borne by the pivoted angular arms a , the contact brushes adjacent to the mains or leads within the tubes or pipes D^2 being identical with the like parts described in connection with Fig. 5.

It will be noticed that the switch boxes B' are provided with openings d in their bases similar to the like openings in the slotted conduit and that they are connected with the 120 drain pipe D' which should have sufficient fall to rapidly carry off any water that might accumulate in any portion of the slotted conduit or the switch boxes, said drain being connected to the sewerage system in any preferred 125 manner to accomplish the result sought in the best manner.

I do not limit myself to the special details of construction hereinbefore described for accomplishing the results sought.

I believe it is broadly new with me to simultaneously furnish current to a moving vehicle and to charge portions only of a supplemental storage battery in successive order,

and my claims are generic in this particular as well.

I believe it is also broadly new with me to inclose a continuous electrical main or circuit in substantially air tight tubes and to connect said tubes with a means of ventilation and drying in such manner as to maintain continuous circulation throughout the system by passing the same air continuously therethrough and my claims are to be construed as generic in this respect.

Having thus described my invention, what I claim, and desire to secure by Letters Patent of the United States, is—

15. 1. A system of electric propulsion consisting of a fixed or stationary generator connected to one or more direct current mains or leads located near the track; a car or vehicle having on board a propelling electric motor 20 and a storage battery operatively connected to the motor, in combination with a conducting trolley or shoe having circuit connections with the motor and the storage battery and means for bringing it into contact and removing 25 it from contact with the current main or mains and additional circuit connections including switching devices, whereby each time the motor is disconnected from the current main or mains different sections of the storage battery are cut into and cut out of circuit 30 and the motor caused to take its propelling current wholly from the storage battery.

2. In an electric railway system an insulated main or lead inclosed in a continuous 35 air tight tube including means for causing the air to move continuously round and round through the tube substantially as described.

3. An insulated conductor of electricity inclosed in an air tight tube operatively connected to a blower or means for causing the same air to circulate continuously round and round through the tube substantially as described.

4. An electric conductor inclosed in an air 45 tight tube, a blower or air pump and a heater all connected together so that the same air is

heated and forced continuously round and round through the tube about the conductor substantially as described.

5. An electric conductor inclosed in an air 50 tight tube connected to a heater a blower and a drier or desiccator all being united so that the same air is heated forced through the tube and dried and the same steps repeated at pleasure substantially as described. 55

6. In an electric railway system a series of vertically pivoted switching devices having insulated journals provided with angular conducting arms and protecting cups or covers which prevent flooding of the conducting 60 parts substantially as described.

7. A current generator having a given electro-motive force and united to a current main operatively connected through a contact trolley or shoe with an electric motor carried by 65 a car or moving vehicle; a sectional storage battery also carried by the vehicle; circuit connections also carried by the vehicle and consisting of a switch for switching the sections of the battery into and out of circuit, 70 and mechanism consisting of hand operative devices adapted to remove the trolley or shoe from connection with the current main and simultaneously vary the sectional connections of the storage battery substantially as 75 described.

8. A system of electric propulsion consisting of a pair of insulated mains connected to a stationary source of current supply and inclosed in an air tight tube connected through 80 a blower and a heater in combination with a series of normally open circuit closing devices located at stated intervals and means carried by the car for closing the circuit from the generator through the mains and a propelling electric motor located on board the car 85 substantially as described.
